CLAIM

The ornamental design for a display stand component, as shown and described.

DESCRIPTION

FIG. 1 is a top front perspective view of a display stand component showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the display stand component that form no part of the claimed design.

The dot-dash broken lines in the figures show boundaries that form no part of the claimed design.

The display stand component is shown in the figures with symbolic breaks in its length. The appearance of any portion or length of the article between the break lines forms no part of the claimed design.
